Filed Feb. 24, 1975, Ser. No. 552,647

Term of patent 14 years

Int. Cl. D7—02

U.S. Cl. D7—128

FIG. 1 is a front perspective view of one embodiment of a microwave oven, showing my new design, with the full front door of the same in partially open condition;

FIG. 2 is a front perspective view of the embodiment of the design shown in FIG. 1 with the full front door in the closed condition;

FIG. 3 is a right side elevational view thereof;

FIG. 4 is a top plan view thereof;

FIG. 5 is a front perspective view of a second embodiment thereof with the full front closure thereof in partially open condition; and

FIG. 6 is a front perspective view of the embodiment of the design shown in FIG. 5 with the full front door in the closed condition.

The right side of the second embodiment of the microwave oven which is not shown, and the bottom plan view of both embodiments are substantially plain and unornamented.

The grill pattern illustrated over small portions of the recessed window areas of FIGS. 1, 2, 5 and 6 continues uniformly throughout such recessed window areas.

I claim:

The ornamental design for a microwave oven, as shown and described.
